HEATING STAND FOR ELECTRIC IRONS

Filed Sept. 10, 1924

2 Sheets-Sheet 1

This perspective view illustrates a book cover assembly. The main body of the cover is labeled 10. A central vertical slot is labeled 12. A horizontal slot or opening is labeled 4. A binding mechanism, labeled 16, is shown on the right side. The top edge of the cover is labeled 10^a. The bottom edge is labeled 10^a. A small detail, labeled 13^b, is shown near the bottom right corner. A coordinate system is indicated with a vertical axis labeled 'z' and a horizontal axis labeled 'x'.

UNITED STATES PATENT OFFICE.

CHARLES A. COOK, OF CHICAGO, ILLINOIS, ASSIGNOR TO C. H. D. ELECTRIC COMPANY, OF CHICAGO, ILLINOIS, A CORPORATION OF ILLINOIS.

HEATING STAND FOR ELECTRIC IRONS.

Application filed September 10, 1924. Serial No. 736,995.

To all whom it may concern:

Be it known that I, CHARLES A. COOK, a citizen of the United States, and residing at Chicago, Cook County, State of Illinois, 5 have invented certain new and useful Improvements in Heating Stands for Electric Irons, of which the following is a specification.

This invention relates to a heating stand 10 for electric irons and particularly irons of the type which are provided with two terminal plugs connected with a heating element within the iron. The object of the invention is to provide a double stand or a 15 stand having two iron receiving platforms for heating irons of that type, the platforms being so arranged that when an iron is placed on one of them the weight of the iron will close electric switches or contacts 20 to cause current to flow through the iron and will automatically break the circuit leading to the other platform. A further object is to provide a construction of the kind specified in which the various contacts 25 are mounted in a suitable supporting member and mechanically connected preferably by levers so that when an iron is placed on one of the platforms, the contacts or switches for that platform will be moved to 30 close a circuit through the iron and the contacts or switches for the other platform simultaneously moved into position to break or interrupt the circuit to the other platform. The foregoing and other useful objects are attained by the construction described in the following specification and 35 illustrated in the accompanying drawing forming a part thereof, and in which—

Fig. 1 is a plan view partly broken away 40 showing the general arrangement of heating stand with the present improvement applied thereto;

Fig. 2 is a transverse sectional view substantially on the line 2—2 of Figure 1;

Fig. 3 is a longitudinal section substantially on the line 3—3 of Figure 1;

Fig. 4 is a diagrammatic view showing the contacts of switches, the manner of operating the same, and the various electrical 50 connections; and

Fig. 5 is an enlarged view of one of the switches or contact arrangements employed.

Referring to the drawings in detail, the numeral 10 indicates generally the heating stand which is provided with two iron re-

ceiving platforms 10^a, 10^b, these platforms being preferably integrally connected to form the stand and being shaped so as to receive an iron as A placed thereon. My improved stand is designed for use with that type of iron which contains a heating element indicated at 11 in Figure 4, and which heating element is provided with two terminal plugs or members 12 which form the means for connecting the iron to an electric circuit.

My present invention relates particularly to the mechanism by which an electric current is caused to flow through an iron placed on either of the platforms 10^a of the stand. 70 Such mechanism comprises a supporting member 13 which is secured to the end of the stand 10 in any suitable manner, which supporting member may be made from lava rock or any other suitable insulating material. The various switches or contact members for causing current to flow through an iron placed on either of the platforms are supported in this member 13. Preferably a plate of insulating material 13^a is placed 80 on either side of the member 13 to insulate the operating parts of the mechanism hereinafter described and the whole may be mounted in a suitable casing or covering 13^b.

Two switches or contact devices are provided for each platform 10^a. Each of these switches comprises a vertically movable contact 14 and a stationary contact 15, the former being arranged to slide up and down in suitable slots formed in the member 13. The contacts 14 for each platform are so spaced and arranged in the member 13 as to receive the terminal plugs 12 of an iron placed on either platform of the stand. The weight of an iron placed on either platform will serve to depress the contacts 14 for such platform and move the same into engagement with the corresponding fixed contacts 15.

Two levers 16 are pivoted intermediate their ends as at 17 to the member 13 or any other suitable part, these levers preferably being arranged in depressions on opposite sides of the member 13. Each lever 16 has one of its ends pivotally connected to one of the movable contacts 14 for one platform and its other end pivotally connected to one of the movable contacts for the other platform. It will thus be seen 110

that when the contacts 14 on one side of the stand are depressed by placing an iron thereon, the corresponding contacts on the other side of the stand will be raised and 5 held out of engagement with the corresponding fixed contacts.

The fixed contacts 15 are connected to the terminals 18 of an electric circuit, one terminal of this circuit preferably being connected to the inner contact 15 on one side of the stand and the other to the inner contact 15 on the other side of the stand. It will also be noted that the outer contact 15 on each 10 side of the stand is connected by means of a suitable conductor 19 to the inner contact 15 on the other side of the stand. By reason of these connections it will be seen that when the terminal plugs 12 of an iron are placed on the contacts 14 for either platform and 15 such contacts are depressed into engagement with the corresponding fixed contacts, an electric circuit will flow through the heating element of the iron so placed. At the same time, the contacts 14 on the other platform 20 will be held out of engagement with their corresponding fixed contacts 15. Each of the movable contacts 14, together with its corresponding contact 15, thus forms in effect an electric switch.

30 As clearly illustrated in Figure 5 of the drawing, the upper face of each stationary contact 15 is preferably provided with a depression 15^a which is adapted to receive the correspondingly shaped lower end 14^a of a 35 movable contact 14. It will also be noted that the upper surfaces of the movable contacts 14 are provided with depressions 14^b into which the terminal plugs 12 of the iron are adapted to rest. It should be noted further that one or both ends of each of the 40 levers 15 is insulated from the pivot pin which connects the same to the movable contacts 14. Such insulation is indicated at 20 in the drawings. This prevents any flow of 45 current from either of the contacts 14 through the levers 16 to the corresponding contact on the other side of the stand.

As will be clearly seen from Figure 1, the upper portion of the member 13 is cut away 50 above the contacts 14 to provide openings into which the terminal plugs 12 of the iron may be inserted. In order to prevent accidental contact with the contact members 14 when an iron is placed on one of the 55 platforms, the iron is preferably provided with a shield 21 secured thereto above the terminal plugs 12 and so positioned as to cover the openings above the contacts 14.

Briefly referring to the operation of the 60 device, it will be understood that when an iron is placed on one of the platforms 10^a with the terminal plugs 12 thereof resting on the movable contacts 14, such contacts will be depressed by the weight of the iron 65 and will be caused to move downwardly and

engage the corresponding fixed contacts 15. Simultaneously the movable contacts 14 for the other platform will be raised through the medium of the levers 16 and will be held out of engagement with the stationary contacts 15 for that platform. The device thus provides an arrangement by which one iron may be heated while the other is being used, and when the used iron is replaced on the platform and the heated one lifted therefrom, the device will automatically operate to cause the current to flow through and heat the iron then on the stand.

Various changes in the details of the foregoing structure may of course be made without departing from the spirit of the invention as outlined in the appended claims.

Having thus described the invention what is claimed as new and desired to be secured by Letters Patent is:

1. A heating stand for electric irons comprising two platforms each adapted to receive an iron, an electric circuit leading to each of said platforms, means operated by placing an iron on either of said platforms for establishing a circuit through the iron so placed, and means for simultaneously interrupting the circuit leading to the other platform.

2. A heating stand for electric irons comprising two platforms each adapted to receive an iron, an electric circuit leading to each of said platforms, separate switch mechanism for controlling the flow of current to each of said platforms, means operated by placing an iron on either of said platforms for closing the switch mechanism for the platform on which the iron is placed and for simultaneously opening the switch mechanism for the other platform.

3. A heating stand for electric irons of the type having two contact members thereon comprising two iron receiving platforms, two electric switches arranged adjacent each of said platforms, the switches for each platform being arranged to cooperate with the contact members of an iron placed thereon, and means operated by the weight of an iron placed on one platform for closing the switches of that platform and simultaneously opening the switches of the other platform.

4. A heating stand for electric irons of the type provided with two contact members, said stand having two iron receiving platforms, each provided with two sets of contacts for closing the circuit through the contact members of the iron, and means operated by the weight of an iron placed on either of said platforms for closing the contacts of the platform on which the iron is placed and simultaneously opening the contacts of the other platform.

5. A heating stand for electric irons comprising two associated iron-receiving plat-

- forms, a fixed contact and a movable contact arranged adjacent each platform, the movable contact for each platform being positioned to be engaged and moved against its respective fixed contact by the weight of an iron, means for causing each of said movable contacts to move away from its respective fixed contact when the other is moved toward its respective fixed contact.
- 10 6. A heating stand for electric irons of the type having two electric terminal plugs; said stand having two iron-receiving platforms, a pair of movable contacts for each platform positioned to be engaged by the 15 plugs of the iron and moved by the weight of the iron, a pair of fixed contacts for each platform arranged to be engaged by said movable contacts, and means for causing the movable contacts for one platform 20 to move away from their respective fixed contacts when the movable contacts for the other platform are moved toward their respective fixed contacts by the weight of an iron.
- 25 7. A heating stand for electric irons of the type having two electric terminal plugs, said stand having two iron-receiving platforms, a pair of movable contacts for each platform positioned to be engaged by the 30 plugs of the iron and moved by the weight of the iron, a pair of fixed contacts for each platform arranged to be engaged by said movable contacts, and lever mechanism associated with said movable contacts for causing the movable contacts for one platform to move away from their corresponding fixed contacts when the movable contacts for the other platform are moved toward their corresponding fixed contacts.
- 35 8. A heating stand for electric irons of the type having two electric terminal plugs, said stand having two iron-receiving platforms, a pair of movable contacts for each platform positioned to be engaged by the 40 plugs of the iron and moved by the weight of the iron, a pair of fixed contacts for each platform arranged to be engaged by said movable contacts, a pair of levers pivotally supported intermediate their ends, each 45 of said levers having one end connected to one of the movable contacts for one of said platforms and the other end connected to one of the movable contacts for the other platform, whereby when the movable contacts for one platform are depressed those for the other platform will be raised.
- 50 9. A heating stand for electric irons comprising two iron-receiving platforms, a pair of vertically slideable contacts for each platform arranged to be moved downwardly by an iron to close a circuit through the iron, and means for causing one pair of said contacts to move upwardly when the other is moved downwardly.
- 55 In testimony whereof I hereunto affix my signature.

CHARLES A. COOK.
